and in Germany May 17, 1930

12 Claims. (Cl. 153—69)

The known types of apparatus employed for producing water-drums of watertube boilers of corrugated form have the great disadvantage that with a mold consisting of upper and lower dies only a single form of drum, that is to say drums with an equal number of corrugations of equal length, can be pressed in each case from the initial straight pieces of tube which are usually of quadrilateral cross-section. In the production of water-drums having different distances between the corrugations, and in those cases where water-drums are to be pressed with various numbers of corrugations, the end sections of which are straight, adjoining the corrugated parts at both ends, entirely differently shaped dies are necessary in each case, the cost of which, quite apart from the reconstruction of the press that would be necessary, considerably increases the cost of production of the corrugated water-drums. Furthermore, in those dies which have an arch-shaped transition between the operative surfaces of the upper and lower dies and the lateral guiding surfaces, there is the disadvantage that when producing these dies the corrugated beak-shaped extension which forms the arch-shaped transition necessitates a very complicated and therefore costly cutting operation.

According to the invention each die surface of the upper and lower dies which produces the dip of the corrugation, consists of a separate arch-shaped part adapted to the form of the corrugation to be produced, these parts being inserted in or secured to the dies, suitable distance pieces being interposed.

By the subdivision of the surface, which in the known dies consists of one piece extending right over all the corrugations, into a number of parts each of which produces the dip of the corrugations, and which are provided to be readily detached and movable, the important advantage is secured that by suitably moving the parts of the dies or by inserting or removing them, water-drums with a large variation of lengths of corrugation and of number can be pressed in the same die.

The invention also relates to the parts which produce the dips of the corrugations. These parts may either consist of rollers which are divided longitudinally, and which bear with their cutting faces against the dies and are held by distance pieces which engage in them and in undercut grooves in the dies, or they may consist of solid rollers, the rollers of the lower die being mounted in suitable recesses therein, while the

rollers of the upper die are held by lateral die guides on the upper die by means of bolts or the like and if necessary are supported in recesses in the upper die.

When divided rollers and distance pieces are used the outer surface of the distance pieces, which outer surface in each case lies opposite divided rollers of the other die, may, according to the invention, be concave in shape to correspond to the peaks of the corrugations forming these distance pieces.

In order that the straight ends of water-drums may be effectively guided when they adjoin the corrugations, special shaping members may be inserted in the undercut grooves in the dies adjoining the roller-shaped portions or the distance pieces—which shaping members together with all the parts that produce the dips of the corrugations and together with the distance pieces are clamped by screw yokes or the like, and if necessary by the use of adapters, and are held immovably in position upon the dies.

As not only the number of corrugations and the length of corrugation of the water-drums to be produced vary, but also their width of corrugation, all the parts may according to this invention be divided in the plane of movement of the dies, and may be adapted to the width of the work by the use of suitable distance pieces.

Furthermore, according to the invention the parts which produce the dips in the corrugations (that is, the rollers, half-rollers or the like) and if necessary also the distance pieces, and the shaping pieces which hold the straight end surfaces of the drums, surround the water-drums to be corrugated at their ends in a curved form with beak-shaped lateral projections. It is cheaper to produce these beak-shaped lateral projections on the various parts than to produce them by a one-piece continuous die, as this work can be carried out by turning or upsetting each single part, whereas hitherto it had to be done by milling the corrugated member.

Apparatus according to the invention is diagrammatically illustrated by way of example in the accompanying drawings:

Figure 1 is a side elevation of a portion of the upper and lower dies of one construction of apparatus according to the invention;

Figure 2 is a section on the line II—II of Figure 1;

Figure 3 is a section on the line III—III of Figure 1;

Figure 4 is a longitudinal section through one part of the upper and lower dies of a modified

construction of apparatus, taken on the line IV—IV of Figure 6;

Figure 5 is a section on the line V—V of Figure 4;

5 Figure 6 is a section on the line VI—VI of Figure 4;

Figure 7 is a plan view of a corrugated water drum produced according to the invention;

Figure 8 is an end view of the same;

10 Figure 9 is a partial side elevation of the upper and lower dies of a modified construction of the apparatus according to the invention.

In the construction according to Figures 1 to 3, 1 and 2 are the upper and lower dies respectively, which both consist of straight-line easily producible profiles, each having a T-shaped longitudinal groove 3. The width of the profiles corresponds to the smallest external width of the water-drums to be produced with the mold.

20 To produce water-drums of other widths with the same mold, an interposed plate 4 of suitable thickness is laid between the die 2 and one of the lateral guides 5 in the lower die (also if necessary in the upper die), and the die 2, 25 the interposed plate 4 and the guides 5 are held together by screws.

The parts 6 of the mold which produce the dips of the corrugations are built up of profiled rollers which are easy to produce on a lathe. These rollers are divided longitudinally and provided at their ends with projecting ribs 6' which are rounded off so as to enclose the edges of the tube to be corrugated. Said rollers are further subdivided at right angles to their 35 longitudinal axes for the insertion of interposed plates 7 and are held apart the distance required for corrugation by distance pieces 9 engaging in grooves 8 and are connected to the dies by the engagement of the distance pieces 9 in the 40 grooves 3 in the dies 1 and 2. The distance pieces 9 may be of any other suitable shape, for example, they may correspond to the disposition of the peaks of the corrugations shown in dotted lines. There is however no necessity to 45 adopt such a measure in the case of small distances between the corrugations, as experience has shown that the radius of the corners of the tube is not reduced at the peak of the corrugation when pressing. The transition from the 50 corrugation to the straight head of the water-drum is provided for by the shaping members 10 and 11, which are guided in the groove 3 and are subdivided along their width for the 55 reception of plates 12. The members 10 and 11 correspond with the rollers 6 and at their ends are provided with rounded off and projecting ribs 10', 11' which enclose the edges of the tube or drum to be produced. All the members 6, 9 and 10 are pressed together by the 60 screws 13 by the help of the yoke 14 and the adapters 15 which may be advantageously guided in the groove 3, and are thus held immovable on the dies 1 and 2.

In the modification according to Figures 4 to 6 the upper die 16 and the lower die 17 are provided with recesses which act as bearings for the solid rollers 18 forming the lower parts of the corrugations of the water-drums. To adapt the lower die to the distance apart of the lateral guides 5 the lower die is provided with an interposed plate 4' of suitable thickness. The solid rollers 18 are divided transversely to their axes, so that by the introduction of interposed plates 7' they can at all times be of the desired length.

75 The parts of the roller and the interposed plates

are held together by screws. The rollers are secured in the dies by any suitable means such as by screws. Variation in the distance between two rollers is not provided in this construction, but this can very readily be obtained by the use of interposed plates or distance pieces already mentioned, which are numbered 9 in Figure 1. Molded (shaping) sections 19 and 20 are mounted in bearings at the ends of the dies 16 and 17 and held by screws. These sections 19 and 20 are employed for obtaining the transition from the corrugation of the water-drums to the straight end section. The sections 19 and 20 may be divided in the construction according to Figures 1 to 3 in similar manner to the sections 10 and 11, so that intermediate plates may be interposed. The shaping members 19 and 20 may be secured to the dies by means other than screws. Furthermore the members 19 and 20 may be so constructed that they surround the die bars as represented for the lower section 20 (Figure 5).

In Figures 4 to 6, the solid rollers 18 and the shaping sections 19 and 20 are provided at their ends with rounded-off projecting ribs 18' and 19', 20', respectively, as may also be seen in Figures 1 to 3 which ribs enclose the edges of the tube or drum intended to be produced.

The apparatus according to the invention has the advantage that the effective pressing surfaces of the dies can be more easily produced, that the length of the corrugations is variable within certain limits and that the number of the water-drum corrugations is independent of the number of corrugations in the press mold. 110 Water chambers of different widths may also be produced with the same press mold by changing the interposed members.

I claim:

1. Means for the production of corrugated water-drums, particularly for watertube boilers, from straight tubes of quadrilateral cross-section, consisting of lower and upper dies disposed between straight lateral guides, said dies being provided with interchangeable shaping members secured thereto, each member producing one dip of the corrugation, the shaping members being held apart on the dies by distance pieces which engage on the one hand in the shaping members and on the other in undercut grooves in the dies. 115

2. Means for the production of corrugated water-drums, particularly for watertube boilers, from straight tubes of quadrilateral cross-section, consisting of lower and upper dies disposed between straight lateral guides, said dies being provided with interchangeably secured roller-shaped shaping members secured thereto, each shaping member producing a dip of the corrugation, the said shaping members being held the 130 right distance apart by distance pieces having concave molding faces each for the formation of a corrugation peak.

3. Means for the production of corrugated water-drums, particularly for watertube boilers, from straight tubes of quadrilateral cross-section, consisting of lower and upper dies disposed between straight lateral guides, said dies being provided with interchangeably secured roller-shaped shaping members secured thereto, each shaping member producing a dip of the corrugation, the said shaping members being held the 145 right distance apart by distance pieces, and of molding members adjoining the last roller- 150

- shaped shaping members and gripping the straight ends of the tubes when pressing.
4. Means for the production of corrugated water-drums, particularly for watertube boilers, from straight tubes of quadrilateral cross-section, consisting of lower and upper dies disposed between straight lateral guides, said dies being provided with interchangeably secured roller-shaped shaping members secured thereto, each shaping member producing a dip of the corrugation, the said shaping members being held the right distance apart by distance pieces, and of molding members adjoining the last roller-shaped shaping members, engaging in undercut grooves in the dies, and gripping the straight ends of the tubes when pressing.
5. Means for the production of corrugated water-drums, particularly for watertube boilers, from straight tubes of quadrilateral cross-section, consisting of lower and upper dies disposed between straight lateral guides, said dies being provided with interchangeably secured roller-shaped shaping members secured thereto, each shaping member producing a dip of the corrugation, the said shaping members being held the right distance apart by distance pieces, and of molding members adjoining the last roller-shaped shaping members, and gripping the straight ends of the tubes when pressing, means being provided which hold close together the roller-shaped shaping members, the distance pieces and the molding members which hold the ends of the tubes.
6. Means for the production of corrugated water-drums, particularly for watertube boilers, from straight tubes of quadrilateral cross-section, consisting of lower and upper dies disposed between straight lateral guides, said dies being provided with interchangeably secured roller-shaped shaping members secured thereto, each shaping member producing a dip of the corrugation, the said shaping members being held the right distance apart by distance pieces, and of molding members adjoining the last roller-shaped shaping members, and gripping the straight ends of the tubes when pressing, screw yokes being provided which hold close together the roller-shaped shaping members, the distance pieces and the molding members which hold the ends of the tubes.
7. Means for the production of corrugated water-drums, particularly for watertube boilers, from straight tubes of quadrilateral cross-section, consisting of lower and upper dies disposed between straight lateral guides, said dies being provided with interchangeable roller-shaped shaping members secured thereto, each member producing one dip of the corrugation, and which carry at their ends rounded-off projecting ribs which enclose the edges of the tube to be corrugated.
8. Means for the production of corrugated water-drums, particularly for watertube boilers, from straight tubes of quadrilateral cross-section, consisting of lower and upper dies disposed between straight lateral guides, having interchangeable roller-shaped shaping members secured to the dies, each shaping member producing a dip of the corrugation, and in which the shaping members are held the right distance apart by distance pieces, the roller-shaped shaping members and the distance pieces being provided at their ends with rounded-off projecting ribs which enclose the edges of the tube to be corrugated.
9. Means for the production of corrugated water-drums, particularly for watertube boilers, from straight tubes of quadrilateral cross-section, consisting of lower and upper dies disposed between straight lateral guides, having interchangeable roller-shaped shaping members secured to the dies, each shaping member producing a dip of the corrugation, and in which the shaping members are held the right distance apart by distance pieces, and of shaping members which adjoin the last roller-shaped shaping members and hold the straight ends of the tube during the pressing, the roller-shaped shaping members, the distance pieces and the shaping members which hold the straight ends of the tubes being provided at their ends with rounded-off projecting ribs which enclose the edges of the tube to be corrugated.
10. Means for the production of corrugated water-drums, particularly for watertube boilers, from straight tubes of quadrilateral cross-section, consisting of lower and upper dies disposed between straight lateral guides relatively adjustable with interchangeable roller-shaped shaping members secured to the dies, each shaping member producing a dip of the corrugation, the said shaping members being divided longitudinally of the tube to be corrugated, and adapters which assimilate the shaping members to the width of the tube to be corrugated being interposed between the parts.
11. Means for the production of corrugated water-drums, particularly for watertube boilers, from straight tubes of quadrilateral cross-section, consisting of lower and upper dies disposed between straight lateral guides relatively adjustable with interchangeable roller-shaped shaping members secured to the dies, each shaping member producing a dip of the corrugation, the shaping members being held the right longitudinal distance apart by distance pieces, the shaping members and the distance pieces being divided longitudinally of the tube to be corrugated, and adapters which assimilate the shaping members and the distance pieces to the width of the tube to be corrugated being interposed between the parts.
12. Means for the production of corrugated water-drums, particularly for watertube boilers, from straight tubes of quadrilateral cross-section, consisting of lower and upper dies disposed between straight lateral guides relatively adjustable with interchangeable roller-shaped shaping members secured to the dies, each shaping member producing a dip of the corrugation, the shaping members being held the right longitudinal distance apart by distance pieces, and of shaping members which adjoin the last roller-shaped shaping members and hold the straight ends of the tube during pressing, the shaping members, the distance pieces and the shaping members which grip the ends of the tube being divided longitudinally of the tube to be corrugated, and adapters which assimilate the shaping members, the distance pieces and the shaping members which grip the ends of the tube, to the width of the tube to be corrugated being interposed between the parts.

MAX ULRICH.
